FASTENER FOR SECURING AN ELECTRICAL DEVICE TO AN OPENING
Albert J. Fischer, P.O. Box 218,
DeLeon Springs Heights, Fla.
Filed Feb. 23, 1962, Ser. No. 175,137
7 Claims. (Cl. 174—52)

This invention relates to a fastener for securing an electrical device to a terminal box and is particularly well suited for the attachment of small transformers of the types used for door bells through the openings provided in outlet boxes by the removal of their knockout discs.

The present invention represents certain improvements over a device for a similar purpose disclosed in the patent to Bladh, 2,819,331, dated January 7, 1958. In accordance with the present invention, when the assembly screw is advanced in a tightening direction, any bending of the fastener resulting therefrom tends to improve the connection with the outlet box both mechanically and electrically.

It is among the objects of the present invention to provide a fastener for securing an electrical device to a terminal box having a wall defining an opening comprising a base portion secured to a surface of the device, an inclined portion diverging from one end of the base portion to define a notch with the surface for reception of the wall, a first leg extending from the other end of the base portion, a second leg substantially parallel to the first extending from the inclined portion defining an acute angle with the base portion, the second leg containing a threaded opening, the first leg containing an opening aligned with the threaded opening and located nearer the base than the threaded opening, and a screw threadedly mounted in the threaded opening and freely movable through the opening in the first leg for engagement with the wall. The inclined portion preferably has a reduced edge for engagement with the wall. The fastener is preferably unitary and is preferably riveted to the surface of the transformer or other device. The maximum distance between the legs is preferably less than a dimension of the opening in order to facilitate introduction of the fastener through the opening during assembly. The maximum dimension of the notch is preferably greater than the thickness of the wall of the terminal box so that the entire thickness of the wall will lie within the notch under assembled conditions.

A more complete understanding of the invention will follow from a description of the accompanying drawings wherein:

FIG. 1 is a front elevation of a conventional outlet box on which a transformer has been mounted in accordance with the present invention;

FIG. 2 is a sectional elevation taken along line 2—2 of FIG. 1;

FIG. 3 is a fragmentary elevation on an enlarged scale taken along line 3—3 of FIG. 2;

FIG. 4 is a further enlarged elevation of the fastener;

FIG. 5 is a plan view of the fastener of FIG. 4; and

FIG. 6 is a plan view of a blank prior to bending to form the fastener.

A conventional outlet box 10 provided with the usual knockout discs 12 is shown in FIG. 1 as having one of its discs removed from its side wall 14 to receive a fastener 16 therethrough for the mounting of a transformer

2

18 or other electrical device in fixed relationship with respect to the wall.

The fastener is provided with a base portion 20 whose lower surface 22 lies in contact with the transformer housing 18 to which it is secured by means of rivets 24 extending through openings 26 in the base portion and registering openings in the transformer housing. An inclined portion 28 diverges from one end of the base portion 20 to define a notch 30 whose maximum dimension exceeds the thickness of the wall 14 so that under assembled conditions as depicted in FIG. 3, the entire thickness of the wall 14 lies within the notch 30. The opposite edges of the inclined portion 28 are dimpled or otherwise reduced to provide biting edges 32 which penetrate the material of the outlet box wall 14 for improved electrical and mechanical engagement. A leg 34 extends from the opposite end of the base portion and a second leg 36 substantially parallel to the leg 34 extends from the inclined portion 28 defining an acute angle with the base portion 20. The second leg 36 contains a threaded opening 38 in alignment with an opening 40 formed through the first leg 34. The opening 40 is located substantially nearer the base 20 than is the opening 38 so that when an assembly screw 42 is introduced through the aligned openings 38 and 40, its thread 44 will engage those of the opening 38 and its unthreaded portion 46 will move freely through the opening 40 so that as the screw is tightened by the use of a screwdriver received in its kerf 46, the abutting end 48 of the screw will bear upon the edge of the wall 14 exposed by the removal of the knockout disc 12 to advance the fastener and transformer 18 towards the left as viewed in FIG. 3 to produce an ever tightening engagement between the wall 14 and the notch 30. In the event that continued tightening of the screw 42 is effected even after an adequate engagement has been produced, there will be a tendency to bend the leg 36 and its adjacent inclined portion 28 in a direction that tends to further tighten the connection between the wall 14 and the fastener 16. This effect is in sharp contrast to that produced with a construction of the type disclosed in the patent above referred to.

In order to facilitate introduction of the fastener through an opening provided by removal of a knockout disc, the maximum distance between the legs 34 and 36 measured in a horizontal direction as viewed in FIG. 3 will be less than the diameter of the opening through the wall 14. With the screw 42 in a retracted position, it will be clear that by introducing the kerfed end of the screw through the opening first, the fastener will then pass freely through the wall 14, whereupon the screw 42 will be advanced to a degree sufficient to produce the desired electrical and mechanical connections.

As will be noted from FIG. 2, the transformer primary leads 50 project from the housing of the transformer 18 on opposite sides of the fastener 16, through the opening formed through the wall 14 of the outlet box for electrical connection to the power leads, not shown.

Whereas only one specific form of the invention has been described with respect to the accompanying drawings, variations suggesting themselves to those skilled in the art are contemplated as falling within the scope of the appended claims.

I claim:

1. A fastener for securing an electrical device to a terminal box having a wall defining an opening comprising

ing a base portion secured to a surface of said device, an inclined portion diverging from one end of said base portion to define a notch with said surface for reception of said wall, a first leg extending from the other end of said base portion, a second leg substantially parallel to the first extending from said inclined portion defining an acute angle with said base portion, said second leg containing a threaded opening, said first leg containing an opening aligned with said threaded opening and located nearer said base than the threaded opening, and a screw threadedly mounted in said threaded opening and freely movable through the opening in said first leg for engagement with said wall.

2. A fastener according to claim 1 wherein said inclined portion has a reduced edge for engagement with said wall.

3. A fastener according to claim 1 wherein said fastener is unitary.

4. A fastener according to claim 1 wherein said fastener is riveted to said surface.

5. A fastener according to claim 1 wherein said device is a transformer.

6. A fastener according to claim 1 wherein the maximum distance between said legs is less than a dimension of said opening.

7. A fastener according to claim 1 wherein the maximum dimension of said notch is greater than the thickness of said wall.
